UNITED STATES PATENT OFFICE

1,965,027

CONTAINER

Wayne W. Bissell, New Castle, Pa.

Application August 9, 1933, Serial No. 684,432

6 Claims. (Cl. 132—82)

My invention relates to improvements in containers, and it consists in the combinations, constructions and arrangements herein described and claimed.

In my prior Patent #1,921,962, Aug. 8, 1933, I disclosed a container having a decorative and protective covering made up of sections or segments with the top of the covering having threaded engagement with the body portion of the inner receptacle. The top thus aided in holding the inner receptacle in position.

An object of the present invention is to provide a receptacle or container having a decorative covering in which the inner receptacle is held fixedly in position without the aid of the top, and in which the top is merely frictionally held so that it may be instantly removed.

A further object of the invention is to provide a receptacle having a decorative outer covering, a portion of which forms a support for a powder puff.

A further object of the invention is to provide a decorative covering of various materials such as glass, porcelain, paper and the like in which the means for suspending the powder puff is provided by a portion of the covering and in which a frictional top or closure member is used.

A further object is to provide a device of the type described in which the inner receptacle may be any one of a number of ordinary paper or cardboard powder boxes.

Other objects and advantages will appear in the following specification and the novel features of the invention will be particularly pointed out in the appended claims.

My invention is illustrated in the accompanying drawings forming part of this application, in which:

Figure 1 is a central vertical section through one embodiment of the invention.

Figure 2 is a bottom plan view of a portion of the device shown in Fig. 1.

Figure 3 is a sectional view of the covering of a modified form, the inner receptacle being shown in side elevation.

Figure 4 is a fragmentary section through a portion of the outer covering and the inner receptacle showing the means for attachment.

Figure 5 is a view similar to Figure 3 of another modified form.

Figure 6 is a section similar to Figure 4 of the form shown in Figure 5.

Figure 7 is a central vertical section through another modified form of the device.

Figure 8 is a perspective view of a spring used in connection with the form shown in Figure 7.

Figure 9 is a central vertical section through another modified form, and,

Figure 10 is a bottom plan view of the form shown in Figure 9.

Referring now particularly to Fig. 1, I have shown therein an inner receptacle 11 which may be made of any suitable material, and which is preferably of cylindrical shape. In this figure the outer covering is shown as consisting of a lower ring-shaped portion 12 having an inwardly extending annular flange 13 underlying the bottom of the receptacle or container 11. The upper edge of the section 12 is flat as shown at 14. Near the upper edge the inner wall of the section 12 is threaded to receive a portion of a threaded ring 15, which is made preferably of metal, and which, as will be seen from the drawings, extends upwardly beyond the top 14 of the lower section 12.

An upper section or segment 16 is provided, this section 16 having a flat bottom arranged to engage the flat top 14 of the section 12, and is threaded internally to engage the threads of the ring 15. The section 16 has an overhanging lip 17, which fits closely against the inner wall of the container 11. The section 16 is also provided with a shoulder 18 and that portion of the section between the shoulder 18 and the lip 17 is extended upwardly, being tapered from the shoulder inwardly and from the lip outwardly as shown at 19 in the drawings. A closure 20 is provided, which is so shaped as to form a frictional fit on the outer portion of the member 19, and to rest on the shoulder 18.

It will be seen that, in the construction described in connection with Figures 1 and 2, the inner container is clamped between the upper and lower sections when these sections are screwed together with the ring 15 as a holding member. The closure 20 may thus be lifted without disturbing the sections 12 and 16 which hold the inner container in fixed position. The tapered member 19 not only acts as a means for receiving the top 20 to effect the closure of the container, but the outwardly tapered inner wall of the member 19 serves to support a powder puff which is placed thereon above the powder which may be contained in the receptacle 1, until such time as the puff is forced downwardly into engagement with the powder.

In Fig. 3 I have shown an arrangement whereby a cardboard container in which toilet powder is sold may be utilized. These card-board contain-

ers usually have an inner liner of paper, parchment or the like, in addition to the main card-board wall. Thus in Fig. 4 I have shown a container or receptacle having a wall 21 which is 5 provided with an inner liner 22 and a bottom portion having an extending flange 23. The drawings show the wall of the container thicker than it actually is, but this is merely for purpose of illustration. The wall of the container has 10 a series of recesses extending inwardly, but not through the inner liner. A metal collar 24 is provided having a threaded portion 24' and ears 25 having lugs 26 arranged to enter the openings as shown in the drawings.

15 In this form of the device the flange 23 underlies a portion of the lower section 28. An intermediate section 29 is provided and an upper section 30 which corresponds to the section 16 in Fig. 1. This upper section, however, is threaded 20 internally to engage the threads 24' so that when the section 30 is screwed down on the section 29, the covering and the container are held rigidly together. The top 31 is frictionally secured to the member 30 and may be removed at will.

25 In Figure 5 I have shown another form in which the inner receptacle 32 has secured to it a metal band 33, which is threaded, and which is provided with downwardly extending lugs 34. These lugs are punched to provide teeth 35 which enter the wall of the container, and which therefore secure the band 33 rigidly in position.

30 In this form of the device a section 36 is threaded to engage the threads on the band 33, and it has an outwardly projecting flange 37 which overlies the section 38 just below it, and is engaged by the lower rim of the top 39. The lower section 40 bears on the flange 41 of the receptacle 35, so that the parts are rigidly held together and the top 39 may be removed or replaced without affecting the assembly of the covering.

35 In those forms of the device set forth in Figs. 3 to 6 inclusive, the card-board receptacle had attached thereto a threaded band. In Fig. 7 I have shown a construction in which it is not necessary to attach a band to the container. In this figure the inner container or receptacle 42 has a flange which is pressed upon by the lower section 43. An upper section 44 is provided 40 which has a lip 45 overhanging the upper edge of the receptacle 42. It also has a tapered inner wall which is threaded to receive a helical member 46. An intermediate covering member 47 bears on the lower section 43.

45 In assembling this form of the device the helical member 46 is placed in the threaded portion of the member 44, the lower and intermediate sections are placed in position, the former engaging the flange of the inner receptacle, and then the section 44 is screwed into position. The helical member 46 will tend to form grooves in the outer wall of the card-board receptacle so that when the flange 48 is finally brought into position to contact with the upper edge of the section 47, then the member 44 will be firmly 50 fixed in position. The frictional top 49 may be removed or replaced without any danger of causing the loosening of the connections between the inner container and the covering.

55 In Fig. 9 I have shown another modified form of the device. In this form the inner receptacle 50 has a threaded portion 51 on the outer wall near the top. The lower part of the receptacle has an inwardly extended boss 52 having a 60 threaded opening arranged to receive a screw

53, which bears on a plate 54. This plate 54 rests against a flange 55 of a lower ring-like member 56, which forms a portion of the covering. An intermediate covering portion 57 is disposed between the covering portion 56 and covering portion 58. The latter has an inwardly extending annular flange 59 arranged to be pressed upon by a top segment 60, which is threaded to engage the threads 51. A top or closure portion 61 fits on the outer surface of the covering segment 60 and is limited in its movement by contact with the upper portion of the covering portion 58. When the segment 60 is screwed down upon the flange 59, it holds the segments below it firmly against the plate which is held in turn to the inner receptacle by means of the screw 53, as shown.

58, which bears on a flange 55 of a lower ring-like member 56, which forms a portion of the covering. An intermediate covering portion 57 is disposed between the covering portion 56 and covering portion 58. The latter has an inwardly extending annular flange 59 arranged to be pressed upon by a top segment 60, which is threaded to engage the threads 51. A top or closure portion 61 fits on the outer surface of the covering segment 60 and is limited in its movement by contact with the upper portion of the covering portion 58. When the segment 60 is screwed down upon the flange 59, it holds the segments below it firmly against the plate which is held in turn to the inner receptacle by means of the screw 53, as shown.

59, which bears on a flange 55 of a lower ring-like member 56, which forms a portion of the covering. An intermediate covering portion 57 is disposed between the covering portion 56 and covering portion 58. The latter has an inwardly extending annular flange 59 arranged to be pressed upon by a top segment 60, which is threaded to engage the threads 51. A top or closure portion 61 fits on the outer surface of the covering segment 60 and is limited in its movement by contact with the upper portion of the covering portion 58. When the segment 60 is screwed down upon the flange 59, it holds the segments below it firmly against the plate which is held in turn to the inner receptacle by means of the screw 53, as shown.

60, which bears on a flange 55 of a lower ring-like member 56, which forms a portion of the covering. An intermediate covering portion 57 is disposed between the covering portion 56 and covering portion 58. The latter has an inwardly extending annular flange 59 arranged to be pressed upon by a top segment 60, which is threaded to engage the threads 51. A top or closure portion 61 fits on the outer surface of the covering segment 60 and is limited in its movement by contact with the upper portion of the covering portion 58. When the segment 60 is screwed down upon the flange 59, it holds the segments below it firmly against the plate which is held in turn to the inner receptacle by means of the screw 53, as shown.

61, which bears on a flange 55 of a lower ring-like member 56, which forms a portion of the covering. An intermediate covering portion 57 is disposed between the covering portion 56 and covering portion 58. The latter has an inwardly extending annular flange 59 arranged to be pressed upon by a top segment 60, which is threaded to engage the threads 51. A top or closure portion 61 fits on the outer surface of the covering segment 60 and is limited in its movement by contact with the upper portion of the covering portion 58. When the segment 60 is screwed down upon the flange 59, it holds the segments below it firmly against the plate which is held in turn to the inner receptacle by means of the screw 53, as shown.

62, which bears on a flange 55 of a lower ring-like member 56, which forms a portion of the covering. An intermediate covering portion 57 is disposed between the covering portion 56 and covering portion 58. The latter has an inwardly extending annular flange 59 arranged to be pressed upon by a top segment 60, which is threaded to engage the threads 51. A top or closure portion 61 fits on the outer surface of the covering segment 60 and is limited in its movement by contact with the upper portion of the covering portion 58. When the segment 60 is screwed down upon the flange 59, it holds the segments below it firmly against the plate which is held in turn to the inner receptacle by means of the screw 53, as shown.

63, which bears on a flange 55 of a lower ring-like member 56, which forms a portion of the covering. An intermediate covering portion 57 is disposed between the covering portion 56 and covering portion 58. The latter has an inwardly extending annular flange 59 arranged to be pressed upon by a top segment 60, which is threaded to engage the threads 51. A top or closure portion 61 fits on the outer surface of the covering segment 60 and is limited in its movement by contact with the upper portion of the covering portion 58. When the segment 60 is screwed down upon the flange 59, it holds the segments below it firmly against the plate which is held in turn to the inner receptacle by means of the screw 53, as shown.

64, which bears on a flange 55 of a lower ring-like member 56, which forms a portion of the covering. An intermediate covering portion 57 is disposed between the covering portion 56 and covering portion 58. The latter has an inwardly extending annular flange 59 arranged to be pressed upon by a top segment 60, which is threaded to engage the threads 51. A top or closure portion 61 fits on the outer surface of the covering segment 60 and is limited in its movement by contact with the upper portion of the covering portion 58. When the segment 60 is screwed down upon the flange 59, it holds the segments below it firmly against the plate which is held in turn to the inner receptacle by means of the screw 53, as shown.

65, which bears on a flange 55 of a lower ring-like member 56, which forms a portion of the covering. An intermediate covering portion 57 is disposed between the covering portion 56 and covering portion 58. The latter has an inwardly extending annular flange 59 arranged to be pressed upon by a top segment 60, which is threaded to engage the threads 51. A top or closure portion 61 fits on the outer surface of the covering segment 60 and is limited in its movement by contact with the upper portion of the covering portion 58. When the segment 60 is screwed down upon the flange 59, it holds the segments below it firmly against the plate which is held in turn to the inner receptacle by means of the screw 53, as shown.

66, which bears on a flange 55 of a lower ring-like member 56, which forms a portion of the covering. An intermediate covering portion 57 is disposed between the covering portion 56 and covering portion 58. The latter has an inwardly extending annular flange 59 arranged to be pressed upon by a top segment 60, which is threaded to engage the threads 51. A top or closure portion 61 fits on the outer surface of the covering segment 60 and is limited in its movement by contact with the upper portion of the covering portion 58. When the segment 60 is screwed down upon the flange 59, it holds the segments below it firmly against the plate which is held in turn to the inner receptacle by means of the screw 53, as shown.

67, which bears on a flange 55 of a lower ring-like member 56, which forms a portion of the covering. An intermediate covering portion 57 is disposed between the covering portion 56 and covering portion 58. The latter has an inwardly extending annular flange 59 arranged to be pressed upon by a top segment 60, which is threaded to engage the threads 51. A top or closure portion 61 fits on the outer surface of the covering segment 60 and is limited in its movement by contact with the upper portion of the covering portion 58. When the segment 60 is screwed down upon the flange 59, it holds the segments below it firmly against the plate which is held in turn to the inner receptacle by means of the screw 53, as shown.

68, which bears on a flange 55 of a lower ring-like member 56, which forms a portion of the covering. An intermediate covering portion 57 is disposed between the covering portion 56 and covering portion 58. The latter has an inwardly extending annular flange 59 arranged to be pressed upon by a top segment 60, which is threaded to engage the threads 51. A top or closure portion 61 fits on the outer surface of the covering segment 60 and is limited in its movement by contact with the upper portion of the covering portion 58. When the segment 60 is screwed down upon the flange 59, it holds the segments below it firmly against the plate which is held in turn to the inner receptacle by means of the screw 53, as shown.

69, which bears on a flange 55 of a lower ring-like member 56, which forms a portion of the covering. An intermediate covering portion 57 is disposed between the covering portion 56 and covering portion 58. The latter has an inwardly extending annular flange 59 arranged to be pressed upon by a top segment 60, which is threaded to engage the threads 51. A top or closure portion 61 fits on the outer surface of the covering segment 60 and is limited in its movement by contact with the upper portion of the covering portion 58. When the segment 60 is screwed down upon the flange 59, it holds the segments below it firmly against the plate which is held in turn to the inner receptacle by means of the screw 53, as shown.

70, which bears on a flange 55 of a lower ring-like member 56, which forms a portion of the covering. An intermediate covering portion 57 is disposed between the covering portion 56 and covering portion 58. The latter has an inwardly extending annular flange 59 arranged to be pressed upon by a top segment 60, which is threaded to engage the threads 51. A top or closure portion 61 fits on the outer surface of the covering segment 60 and is limited in its movement by contact with the upper portion of the covering portion 58. When the segment 60 is screwed down upon the flange 59, it holds the segments below it firmly against the plate which is held in turn to the inner receptacle by means of the screw 53, as shown.

71, which bears on a flange 55 of a lower ring-like member 56, which forms a portion of the covering. An intermediate covering portion 57 is disposed between the covering portion 56 and covering portion 58. The latter has an inwardly extending annular flange 59 arranged to be pressed upon by a top segment 60, which is threaded to engage the threads 51. A top or closure portion 61 fits on the outer surface of the covering segment 60 and is limited in its movement by contact with the upper portion of the covering portion 58. When the segment 60 is screwed down upon the flange 59, it holds the segments below it firmly against the plate which is held in turn to the inner receptacle by means of the screw 53, as shown.

72, which bears on a flange 55 of a lower ring-like member 56, which forms a portion of the covering. An intermediate covering portion 57 is disposed between the covering portion 56 and covering portion 58. The latter has an inwardly extending annular flange 59 arranged to be pressed upon by a top segment 60, which is threaded to engage the threads 51. A top or closure portion 61 fits on the outer surface of the covering segment 60 and is limited in its movement by contact with the upper portion of the covering portion 58. When the segment 60 is screwed down upon the flange 59, it holds the segments below it firmly against the plate which is held in turn to the inner receptacle by means of the screw 53, as shown.

73, which bears on a flange 55 of a lower ring-like member 56, which forms a portion of the covering. An intermediate covering portion 57 is disposed between the covering portion 56 and covering portion 58. The latter has an inwardly extending annular flange 59 arranged to be pressed upon by a top segment 60, which is threaded to engage the threads 51. A top or closure portion 61 fits on the outer surface of the covering segment 60 and is limited in its movement by contact with the upper portion of the covering portion 58. When the segment 60 is screwed down upon the flange 59, it holds the segments below it firmly against the plate which is held in turn to the inner receptacle by means of the screw 53, as shown.

74, which bears on a flange 55 of a lower ring-like member 56, which forms a portion of the covering. An intermediate covering portion 57 is disposed between the covering portion 56 and covering portion 58. The latter has an inwardly extending annular flange 59 arranged to be pressed upon by a top segment 60, which is threaded to engage the threads 51. A top or closure portion 61 fits on the outer surface of the covering segment 60 and is limited in its movement by contact with the upper portion of the covering portion 58. When the segment 60 is screwed down upon the flange 59, it holds the segments below it firmly against the plate which is held in turn to the inner receptacle by means of the screw 53, as shown.

4. In a container, a receptacle having a closed bottom and open at its top, said receptacle being provided with external threads near its open end and being provided with an abutment at its bottom, a decorative covering comprising a plurality of sections, and a threaded ring arranged to engage the threads on said receptacle and having a portion arranged to bear on said covering sections to clamp them together against said abutment.
5. In a container, a receptacle having a closed bottom and open at its top, said receptacle being provided with external threads near its open end and being provided with an abutment at its bottom, a decorative covering comprising a plurality of sections, and a threaded ring arranged to engage the threads on said receptacle and having a portion arranged to bear on said covering sections to clamp them together against said abutment, said threaded ring having an outer cover-receiving surface, and a cover arranged to frictionally engage the surface.
6. In a container, a receptacle having a closed bottom and open at its top, said receptacle being provided with external threads near its open end and being provided with an abutment at its bottom, a decorative covering comprising a plurality of sections, a threaded ring arranged to engage the threads on said receptacle and having a portion arranged to bear on said covering sections to clamp them together against said abutment, said threaded ring having an outer cover-receiving surface, and a cover arranged to frictionally engage the surface, the interior surface of the ring being flared outwardly above the container.
